UNITED STATES PATENT OFFICE.

CHARLES SCOTT-SNELL, OF LONDON, ENGLAND.

ADVERTISING OR THE LIKE.

SPECIFICATION forming part of Letters Patent No. 731,075, dated June 16, 1903.

Application filed February 6, 1902. Serial No. 92,932. (No model.)

To all whom it may concern:

Be it known that I, CHARLES SCOTT-SNELL, a subject of the King of Great Britain and Ireland, residing at 51 Victoria street, Westminster, London, England, have invented certain new and useful Improvements in Advertising or the Like, (for which I have made application for Letters Patent in Great Britain, No. 15,870, dated August 7, 1901,) of which the following is a specification.

This invention relates to advertising apparatus of the kind whereby an advertisement is mechanically caused to change in character or to intermittently appear and disappear.

The object of the invention is to provide an apparatus of simple construction by which an advertisement may be gradually exposed and then after complete exposure changed or obliterated.

The invention consists in disposing a number of bars adjacent to one another in the same plane, the combined surfaces or peripheries presenting an advertising-surface, each bar bearing a component part of the whole advertisement, and then successively rotating said bars by means of a chain provided with a claw or claws adapted to engage projections on or connected to the bars, means being provided to retain the bars in register after rotation, such means, however, releasing the bars when required either successively or simultaneously, as hereinafter described.

Referring to the accompanying drawings, Figure 1 is an elevation of an apparatus embodying the invention and designed to give a gradual or progressive exposure and change or obliteration, Figs. 2, 3, and 4 being details corresponding thereto. Fig. 5 is a further detail relating to Fig. 1. Fig. 6 is a view, partly in plan and partly in section, of a modified form. Fig. 7 is a detail relating to Fig. 6. Fig. 8 is a transverse sectional view of the apparatus shown in Fig. 6. Fig. 9 is a view, partly in side elevation and partly in section, of another modification. Fig. 10 is a plan view, partly in section, of the modification shown in Fig. 9. Fig. 11 is a detail transverse sectional view of the modified form of Fig. 9. Fig. 12 is a detail view of a further modification.

In carrying out the invention according to one form, as illustrated in Figs. 1 to 5, the bars

a, carrying component parts of an advertisement upon their peripheries, are arranged in vertical parallel series in a framework *b*, provided with bearing-plates *c* for the axle-pins *d* at the top and bottom of the bars. At one end of all the bars, preferably at the top, projections *h* are provided, adapted to be engaged by one or more claws *i* upon a chain *f*, traveled by a sprocket-wheel *g*, so that the bars are successively rotated. In order to keep the bars in register after rotation, the chain-blocks *j* are extended and adapted to engage the faces or ends of the projections *h*, thus preventing any movement on the part of the bars until a claw engages a projection, a suitable gap *i* being formed adjacent to each claw to allow rotation of the bar. If a quarter-rotation of each bar is desired at a time, four projections *h* are provided, as shown, thus furnishing four surfaces to be used for different advertisements; but any other convenient number may be used. By this form of apparatus the exposure and change of advertisement are of a gradual or progressive nature. Guide-pins *22*, supported on a bar *23*, attached to the framework, insure engagement of the claws with the projections.

When it is desired that the advertisement after having been progressively exposed shall be instantaneously changed, the mode of retaining the bars in register above described is inapplicable; but the bars may be still rotated successively by a similar claw-and-chain device. Such an apparatus is illustrated in Figs. 6 to 8. In this case the bars which are provided with projections *h*, as before, engaged successively by one or more claws *i* upon a chain *f*, are retained in register after rotation by means of pawls *l*, engaging ratchets *k* on the bars. The pawls are simultaneously released to allow a simultaneous return movement of all the bars under the action of returning-springs. The release of the pawls is caused by a projection *t* upon the chain engaging a lever *u* upon one end of a cross-shaft *v*, a lever *w* upon the other end of which at the same time engages a projection *x* upon a rod *q* and moves the same against the action of a spring *s*. The pawls which are pivoted on a bar *n* of the framework are all formed with slotted extensions *o*, engaged by pins *p* on the rod *q*, so that movement of

the latter, as above described, results in a simultaneous release of the pawls.

By suitably disposing the projection *t* upon the chain and by using several claws, such as *i*, a succession of advertisements may be exposed before the bars are released and instantaneously brought back to the initial position. The bars are returned by the springs *m*.

The mode of holding the bars in register and simultaneously changing the advertisement may be accomplished by causing the bars to rotate still farther onward instead of backward. Such an apparatus is illustrated in Figs. 9 to 12. In this case the projections *h* are not directly fixed to the bars, but to boxes *z*, which are mounted loosely upon the axle-pins *d* at the top of each bar. The boxes are connected by spiral springs *2* to the axle-pins, and besides the projections *h* are provided with additional projections *3*. The former, *h*, are engaged successively by claws *i i*, the first of which winds up the springs and the second imparts a partial rotation therethrough to the rollers. The projections *3* are engaged by the chain-blocks *j* to prevent backward rotation or to hold the bars in register, suitable gaps *4 4* being provided adjacent to the claws to allow rotation at the desired times. The forward rotation of the rollers is limited by stops *5*, which engage with the pawls *6*, carried by a shaft *q*, which is partially rotated in the bearings *r*, so as to simultaneously release all the stops *5*, and therefore all the rollers, when an instantaneous change of the completely-exposed advertisement is desired. This release is effected in one convenient manner by a projection *7* on the chain engaging a lever *8* and imparting motion, through a shaft *9*, to a second lever *10*, in contact with an arm *11* upon the shaft *q*, or, as shown in Fig. 12, a worm-wheel *12*, mounted on the shaft *9*, is rotated by a worm-shaft *15*, which is provided with a sprocket-pinion *16* directly in gear with the driving-chain.

In order to prevent a backward rotation of the spring-boxes after the springs have been wound, spring-pawls *17* and teeth *18* may be used in addition to or instead of the arms *3*. An initial tension may be applied to the springs *2* before the spring-boxes are placed in position, so as to render the rotation of the rollers more effective, in which case pins *19* are provided on the rollers to engage within slots *20* in the boxes, so as to always retain the springs under tension.

Having thus described my invention, what I claim as new, and desire to secure by Letters Patent, is—

1. An advertising apparatus consisting of a number of bars disposed adjacent to one another in the same plane so that the combined peripheries present an advertising-surface, each bar bearing a component part of the complete advertisement, projections on the ends of said bars, a chain, claws thereon for engaging said projections for successively rotating said bars, and extended blocks on the chain for engaging said projections to retain the bars in register, as hereinbefore described. 60

2. An advertising apparatus consisting of a number of bars disposed adjacent to one another in the same plane so that the combined peripheries present an advertising-surface, each bearing a component part of the advertisement, projections on the ends of the said bars, a chain, claws thereon for engaging said projections for successively rotating said bars and extended blocks on the chain for engaging said projections to retain the bars in register, the said chain having gaps adjacent 70 to the claws to allow rotation of the bar, substantially as described. 75

In witness whereof I have hereunto set my hand in presence of two witnesses.

CHARLES SCOTT-SNELL.
